UNITED STATES PATENT OFFICE

RAUL PATERAS PESCARA, OF PARIS, FRANCE

WASTE HEAT APPARATUS

Application filed June 29, 1927, Serial No. 203,444, and in France July 7, 1926.

My invention relates to apparatus for producing motive power used in conjunction with gas producers or oil distilling apparatus.

5 The principal object of my invention is to provide a means for recovering the greater portion of the heat which is ordinarily carried away by the gas leaving an apparatus of the type indicated.

10 A more specific object of the invention is to utilize the heat thus recovered for re-heating air compressed by means of a motor compressor of the direct driven direct acting internal combustion type, more fully described in my prior Patent No. 1,691,737, of Nov. 13, 1928, which feeds a turbine in such wise that all or a part of the recovered heat may be transformed into mechanical work during expansion of said air thus compressed and reheated.

15 Other objects of the invention will be obvious to those skilled in the art with reference to the following description taken in connection with the accompanying drawing 20 in which—

The single figure is a diagrammatic view of an apparatus conforming to my invention.

Referring to the drawing, a motor-compressor 10 of the direct driven direct acting internal combustion type, more fully described in my prior patent hereinbefore referred to, feeds a turbine 11 and a gas producer 12 feeds the motor cylinder of the compressor 10 with gas. The compressing cylinders of compressor 10 are connected to a tank 14 by means of pipes 20. A pipe line 13 connects the tank 14 to the turbine 11 and disposed in said pipe line is a reheater 15 which is connected to the producer 12 by means of a pipe 16. The gas circulating in said reheater heats the air being supplied under constant pressure to the turbine 11. The said gas is led through a pipe 17 to the motor cylinder of compressor 10 where it is consumed in driving said compressor.

A second reheater 19 is disposed in the pipe line 13 between the reheater 15 and the turbine 11. Said reheater is connected

to the exhaust pipe 18 of compressor 10 in such a manner that the burned gases may pass therethrough and thus further heat the air in pipe line 13 being supplied to the turbine 11 under constant pressure. There 55 is thus recovered a certain portion of the heat in the exhaust gases of the compressor.

The arrows clearly show the direction taken by the compressed air and that taken by the gases during operation. The air 60 which arrives at the turbine 11 possesses under these conditions a calorific richness much greater than that which it contained when leaving the compressor 10. The air expanding in the turbine 11 is therefore able 65 to produce more work than that which was required to compress it. The gain in work produced in the turbine depends largely upon the conditions under which the air is compressed and hence upon the amount of 70 heat taken on from the gas from producer 12 as well as that from the exhaust 18.

Many variations in my apparatus may be made by those skilled in the art without departing from my invention, since 75

What I claim is—

1. In an apparatus of the type described an internal combustion air compressor of the direct driven direct acting type having a main driving cylinder and a plurality of compressing cylinders, an air turbine connected to said compressing cylinders, means for supplying said driving cylinder with a combustible fluid at a temperature greater than that of the air compressed by said compressor and means for imparting a portion of the heat in said combustible fluid to the air furnished to said turbine for the purpose specified. 80

2. In an apparatus of the type described 90 an internal combustion air compressor of the direct driven direct acting type having a main driving cylinder and a plurality of compressing cylinders, an air turbine connected to said compressing cylinders, means for supplying said driving cylinder with a combustible fluid at a temperature greater than that of the air compressed by said compressor, means for expelling the exhaust gases from said driving cylinder, means for 95

imparting a portion of the heat in said combustible fluid to the air furnished to said turbine and means for imparting additional heat to the air furnished said turbine from the exhaust gases expelled from said driving cylinder for the purpose specified.

3. In an apparatus of the type described an internal combustion air compressor of the direct driven direct acting type having 10 a main driving cylinder and a plurality of compressing cylinders, a tank connected to said compressing cylinders, an air turbine, a pipe line connecting said tank to said air turbine, a plurality of heat-exchange devices disposed in said pipe line, a gas producer for said compressor, a pipe connecting said gas producer with one of said heat exchange devices, an admission pipe connecting said driving cylinder with said same 20 heat exchange device and an exhaust pipe for said driving cylinder connected with the other of said heat exchange devices for the purpose specified.

In testimony whereof I have signed my 25 name to this specification at Barcelona, Spain, this 14th day of June, 1927.

RAUL PATERAS PESCARA.
